UNITED STATES PATENT OFFICE

2,285,258

LINE POSITION CONTROL DEVICE FOR
PAPER FORMS

Charles R. Doty, Yonkers, N. Y., assignor to International Business Machines Corporation, New York, N. Y., a corporation of New York

Application April 6, 1940, Serial No. 328,305

5 Claims.

(Cl. 197—5)

This invention relates to a method for maintaining continuous forms of paper or the like operating in different printing machines in a pre-determined relationship with respect to the printing line of each machine, so that similar printed records are effected simultaneously on corresponding portions of the forms in each machine.

In office work where it is desirable to obtain a plurality of identical printed records without resorting to carbon copies, a customary procedure is to connect one or more typewriters for control by a master typewriter. Continuous paper forms are connected with the paper feed devices of each machine in corresponding relationship and paper feeding is controlled by the usual carriage return key. Should any of the forms get out of step with the form in the master typewriter, there is often considerable nuisance and loss of time in getting it back in proper relationship. It will be appreciated that this difficulty is apt to be even more a source of bother if the various typewriters are located at considerable distances from the master typewriter.

It is therefore the general object of the invention to provide, in a multiform printing system, an improved method for maintaining a corresponding operating relationship among the paper forms operating in different printing machines including a novel correction control means for re-establishing that relationship should the forms for any reason get out of step. According to the invention, a cam and a set of control contacts are associated with each typewriter, the cam being geared for rotation by the same mechanism which drives the platens of the typewriters. The contacts are arranged to be operated once each revolution of their related cam, i. e., once each revolution of the platen. Depression of a special control button causes a series of impulses to be sent out over a common line connecting the various typewriters. Should any of the typewriters be lagging in so far as the paper feed is concerned, it is promptly brought up to the proper position as determined by the master typewriter. In the event that the paper form at any of the secondary typewriters gets ahead of the form in the master typewriter, it is automatically caused to wait for the master form. By this simple arrangement the operator of the master typewriter may conveniently keep the printed forms in the other typewriters in proper relationship.

Other objects of the invention will be pointed out in the following description and claims and

illustrated in the accompanying drawing, which discloses, by way of example, the principle of the invention and the best mode, which has been contemplated, of applying that principle.

5 In the drawing:

Fig. 1 shows a portion of the typewriter mechanism including the printing actuating means and the control cam and contacts associated with the platen.

10 Fig. 2 is a schematic wiring diagram of the control for keeping paper forms of two different typewriters in a fixed relationship.

For illustrative purposes, this invention is shown as embodying a well-known type of power operated typewriter such as that shown and described in detail in the United States Patent No. 1,777,055, issued to Russell G. Thompson and dated September 30, 1930.

Referring now to Fig. 1, well-known means are provided for actuating the type bars 16, comprising a constantly rotating roller 10, cooperating with a series of individual power units each comprising a cam 11, the engagement of the cams with the roller being controlled selectively by the character key bars 17.

Any suitable means may be provided to rotate the power roller, in the direction indicated by the arrow, which is adapted to cooperate with two rows of cam units arranged in the front and rear 30 of the roller. The cam 11 may be pivoted on one arm of a bell crank lever 12 which in turn is pivoted to the frame of the machine, as indicated generally by reference character 13, the other arm of the said bell crank lever being operatively connected with an arm of the bell crank lever 14 by means of link 15. Another arm of the said lever 14 is connected to the type bars 16 in a well-known manner, so as to effect operation of the type bars or any other suitable means connected to the bell crank levers upon selective operation of the controlling key bars 17.

45 The pivoted bell crank lever 12 is operated by the associated cam 11 whenever the latter engages the driven roller; the engagement of the cam with the roller is controlled by means of the associated control key bar 17 in a manner which will now be briefly described.

An impeller-arm 18 associated with cam 11 is urged by the associated coil spring 19 against one 50 of the impeller-lugs 20, which at the time is in the lower position, and tends to turn the cam in a clockwise direction. This is prevented, however, by the engagement of one of the detents 21 on the cam, with the upper stop lug 22 on the stop lever 23. If, however, the corresponding key

bar is operated, the bifurcated lower end of extension arm 24 associated with one of the said key bars 17 engages an arm 25 at the upper end of the stop lever 23 which is provided with an offset projection at its end extending laterally through an opening in the bell crank lever 12. The arm 25 of the stop lever 23 is then swung rearwardly or to the left as viewed in Fig. 1 about the pivot 26 and its lower end forwardly or to the right as viewed in this figure, thus releasing the cam, which then turns under the influence of the spring urged impeller-arm 18. In doing so the upper serrated lobe of the cam is brought into engagement with the power roller, which turns in a counterclockwise direction and therefore causes a continued rolling movement of the cam until the high point has been reached and passed. This causes the whole cam unit to swing around the pivot 13 so as to pull down the corresponding link and actuate one of the type bars or any other mechanism with which the cam unit may be connected.

After the high point of the cam is passed the cam loses contact with the roller, but the said impeller-arm 18 tends to continue the rotation thereof by engaging the second impeller-lug 29 of cam 11 until the second detent 21 engages one of the stop lugs. Since the half rotation of the cam consumes only a small fraction of a second, it is difficult to release the key bar within this short interval, so that it is the lower lug 28 which is first engaged, but upon the release of the key bar and the return of the stop lever 23 to normal position, this lug 28 disengages the detent, whereupon the impeller-arm rotates the cam slightly, and the said detent then engages the upper stop lug 22.

It is obvious then that depression of a key bar releases the revolvably mounted cam to engage and be actuated by the power roller in turn operating the associated bell crank lever and its attached links to cause the associated mechanism such as the type bars and other operating mechanisms to be operated. It is to be understood that an individual cam unit is provided for each type bar or other functional mechanism associated therewith.

The action of the cam mechanism has been described with respect to one of the rear bank of cam units; in the case of those of the forward bank the operation is analogous, but the directions of movement and the order of operation of the stop lugs is reversed.

The description thus far has been limited to mechanisms and control members operated by double lobe cam units. In power operated typewriters of the type shown herein, operations such as carriage return, back space, and tab-skip are effected under control of single lobe cams. The carriage return mechanism in its operation is accompanied by a line spacing operation in the customary manner, and it is the control of these operations which is the main concern of the disclosed embodiment of the invention. For a description of the carriage return mechanism per se reference should be made to U. S. Patent No. 1,735,450. According to Fig. 1, this mechanism is controlled by a carriage return key bar 41 which may be depressed manually or by virtue of the energization of a connected solenoid 60 as described later. The said key bar controls a single lobe cam 44, the mechanism associated with this cam being connected for operation of the carriage return apparatus (not shown) through the medium of link 45.

Depression of key bar 41 provides the necessary motion through bifurcated arm 24a and arm 25a to move the stop lever 23a to the right, and hence to permit the impeller arm 18a to engage the impeller lug 20a for urging the cam 44 into engagement with the power roller 10 under the impetus of the coil spring 19a. Cam 44 then turns with the roller 10 for one revolution during which time the bell crank lever 12a is rocked about its pivot 13a to impart the necessary movement to link 45 to effect a carriage return operation. Should the carriage be already returned, at this time, the movement of link 45 simply causes a line space to occur.

It will be noted that cam 44, which rotates a complete revolution upon its release, is provided with only one detent (21a). The structure of the single lobe cam unit further differs from that described for cam 11 and over the customary carriage return control mechanism in that only one stop lug (22a) is provided on stop lever 23a. This special change in the usual structure, for purposes which will become apparent later herein, permits cam 44 to make repeated revolutions during the continued depression of carriage return key lever 41 by virtue of the fact that the stop lug 22a clears the detent 21a as long as lever 41 is in the depressed condition. Upon release of lever 41, lug 22a is returned to its normal position in the path of detent 21a so as to latch up the cam when the detent comes into engagement with the lug.

The operations involved in the control of the carriage return and printing mechanism having now been described, it will be understood that if two or more of these typewriters are to be connected for printing the same information on different continuous forms, control means must be provided for maintaining those printed forms in corresponding relationship in order to obtain satisfactory results. This control means is illustrated schematically in Fig. 2, where a remotely located typewriter is shown under control of the master typewriter. The master station is indicated generally at M and the remote station at R.

It will be noted that in the upper part of Fig. 1 a platen 50 is provided with pins 51 protruding therefrom adapted to fit in spaced holes 50 along the edges of continuous paper forms in the well-known manner to insure positive paper feeding upon spacing of the platen. Integral with the platen is a gear 52 which meshes with another gear 53 so as to drive a cam 54 in the direction indicated by the arrow as the platen is advanced. Gear 53 and cam 54 are fastened together and are rotatably mounted on a shaft 55 which is attached to the frame of the machine. The cam is circular with the exception of a single high point 55 on its periphery which is arranged to effect the opening of a set of normally closed contacts 56, 57 located in the path of rotation thereof and mounted in a convenient manner on the frame of the machine, but obviously enough insulated from the frame and from cam 54 by suitable insulating material.

It will be understood that continuous paper strips are inserted in the machines at the start of operations in such a manner that the contacts are in the open position for the starting line of one of the forms of each strip. The gear ratio between gears 52 and 53 is chosen in accordance with the size of the individual forms so that one revolution of cam 54 corresponds to the distance from the starting line of one form to the start-

ing line of the next. Thus, a definite relationship between the position of the paper and the condition of the contacts is established for each machine. The normal carriage return mechanism may effect line spacing of the machines at stations M and R in the customary manner.

Assume, however, that a portion of a particular form has been typed at each station and that either a mistake has been made or for some reason the next printed information is desired to be placed on the starting line of the next form. In situations of this nature the utility of the present invention is best revealed and the circuits which bring about the desired results will now be set forth.

Upon depression of a button 59 located near the master typewriter, a circuit is completed from the negative side of the battery B through button contacts 61, 62, cam contacts 56, 57 assumed now to be closed since the form is in other than starting line position, carriage return solenoid 60, relay coil 70, to positive side of battery B. The circuit just traced causes energization of the relay 70 to close its contact switch 70a and complete a circuit from negative side of battery B, resistance r, switch 70a, cam contacts 56, 57, carriage return solenoid 60, relay 70, to positive side of battery B. The carriage return solenoid is thus energized to cause repeated carriage return operations under control of the single lobe cam 44, as previously described, until cam 54 opens contacts 56, 57 to break the circuit. Simultaneously with depression of the button 59, contacts 63, 64 also close and a circuit is completed to the remote typewriter in a similar manner, first picking up relay 70' to close its associated contact switch 70'a and then providing a holding circuit through the carriage return solenoid 60' and the relay 70' until the cam 54' opens its contacts 56', 57' to break the circuit.

An extra set of contacts 66', 67' is located so as to be operated by the cam 54' when the high point of the cam reaches the position shown in Fig. 2. The latter contacts, upon closure, complete a simple circuit from positive side of battery B1 via wire 68 to contacts 66', 67' now closed, wire 69, indicating lamp L to negative side of battery B1. The lighting of lamp L at the master typewriter indicates that the cam 54' of the secondary typewriter is in the position shown. The operator may visually check as to whether the master machine is in the position shown and, since the indicating lamp signifies that the secondary machine is in corresponding position, operations may then continue with the operator being assured that the printing on the continuous forms at each typewriter is effected on corresponding printing lines thereof.

Although the control for only two machines has been disclosed in Fig. 2, it will be appreciated that a great number of machines may be controlled from the master machine by simply increasing the number of contacts which are operated by the button 59 and adding circuits for each machine similar to those shown in this figure. Should the number of contacts become very large under this method, provision may be made to obviate such a difficulty in permutation arrangements in any well known manner without departing from the spirit of the present invention.

While there has been shown and described and pointed out the fundamental novel features of the invention as applied to a single modification, it will be understood that various omissions

and substitutions and changes in the form and details of the device illustrated and in its operation may be made by those skilled in the art without departing from the spirit of the invention. It is the intention therefore to be limited only as indicated by the scope of the following claims.

What is claimed is:

1. In apparatus for maintaining registration of record strips in a plurality of printing devices, each device cooperating with a continuous strip divided into forms with a starting line position on each form; strip feeding means for feeding each of said strips relative to said printing devices to receive printed records in different locations thereon, individual means controlled by the feeding means in timed relation with the feeding of the strips to indicate when the starting lines of the forms on said strips are opposite the printing devices, a common control means responsive to manual operation to effect continual operation of the strip feeding means, and means controlled by the individual indicating means for automatically rendering the control means ineffective to cause further operation of each of said strips by the feeding means after the starting line on a form of said strip has arrived opposite its related printing device.
2. In an apparatus for maintaining the alignment of record strips in a plurality of printing devices, said record strips being in the nature of interconnected forms associated with said devices for receiving printed records, each form having a starting line position thereon; the combination of line spacing means and control means therefor for causing line spacing of said strips as required during the normal course of operation of the printing devices, individual means controlled by the line spacing means in synchronism with the spacing of the strips to indicate when the starting lines on the forms of said strips are opposite the printing devices, a common auxiliary control means for said line spacing means responsive to manual operation for causing sustained operation of the said line spacing means, and means controlled by the individual indicating means for automatically rendering the auxiliary control means ineffective to cause further line spacing of each strip upon arrival of the starting line on a form of said strip opposite its related printing device.
3. In an apparatus for maintaining the alignment of record strips in a plurality of printing devices, said record strips being in the nature of a plurality of interconnected forms associated with said devices for receiving printed records, each form having a starting line position thereon; the combination of individual line spacing means and common control means therefor for causing normal line spacing of said strips as required for the spacing of the printed records, special control circuits for the individual line spacing means including a common circuit closing means responsive to manual operation for closing said circuits to effect sustained line spacing of the said strips by the said line spacing means, a set of normally closed contacts in each of said circuits, and means movable in synchronism with each of the line spacing means for opening the associated special control circuit to prevent further line spacing of each strip as said strip arrives at the starting line position, regardless of the continued manual operation of the circuit closing means.
4. In apparatus comprising a plurality of

printing devices with rotatable platens adapted to receive record strips in the nature of a plurality of interconnected forms, each form having a starting line position thereon; the combination of individual line spacing means for said platens, normal control means cooperating with said line spacing means for rotating the platens so as to line space the strips at the different printing devices in corresponding relationship, a rotatable cam geared to each platen for rotation therewith, the gear ratio being such that one revolution of the cam corresponds to the line spacing of a strip from the starting line position of one form to the starting line position of the next form, auxiliary control means also cooperating with the line spacing means including a plurality of circuits, one for each printing device, and a common control switch adapted to be called into operation manually to complete said circuits to effect continued rotation of said platens, and a set of normally closed contacts in each of said circuits and adapted to be opened by the platen controlled cam of the related printing device as a form of the strip in said device arrives at the starting line position to prevent further rotation of said platen by the auxiliary control means.

5. In apparatus for maintaining alignment of record strips in printing devices at remotely located stations so that like records may be printed thereon, said strips being divided into a plurality of continuous forms, each form having a starting line position; the combination of individual feeding means for said strips at each station, means controlled by each of the feeding means in timed relation with the feeding of the strips for indicating when the starting line of a strip arrives opposite its related device, a common control means at the first station operable manually to cause sustained operation of the individual feeding means at each station, means controlled by the starting line indicating means of each device for rendering each individual feeding means ineffective upon arrival of the corresponding strip in a starting line position, and means further controlled by the starting line indicating means of the device at a second station as an incident to the operation thereof for signalling to the first station that the strip at the second station has arrived in starting line position.

CHARLES R. DOTY.
